UNITED STATES PATENT OFFICE.

BAGSTER ROADS SEABROOK, OF MISHAWAKA, INDIANA.

TONE-CONTROLLING HORN SUPPORT.

Application filed September 3, 1921. Serial No. 498,387.

To all whom it may concern:

Be it known that I, BAGSTER ROADS SEABROOK, a citizen of the Dominion of Canada, residing at Mishawaka, in the county of 5 St. Joseph and State of Indiana, have invented certain new and useful Improvements in Tone-Controlling Horn Supports, of which the following is a specification.

My invention relates to improvements in 10 tone controlling horn supports and it more especially comprises the features hereinafter pointed out in the annexed claims.

The purpose of my invention is to provide a tone controlling support that is located at a point on the neck of the horn which receives the first impact of passing sound waves as they issue from the tone arm; that insures rigidity of the horn not otherwise attainable; that overcomes modifying horn vibrations; that admits of free amplifications without incurring vibrations set up by the natural periodicity of the horn itself.

With these and other ends in view, I 25 illustrate in the accompanying drawing such instances of adaptation as will disclose the broad underlying features without limiting myself to the specific details shown thereon and described herein.

30 Figure 1 is a side elevation partly in section of a phonograph horn in its associative relation to its supports, etc.

Fig. 2 is a front elevation of Fig. 1 partly in section.

35 Fig. 3 is a view similar to Fig. 1 showing an alternative under-saddle.

Fig. 4 is a front elevation of the salient features of Fig. 3.

Fig. 5 is an enlarged elevation partly in 40 section, of a tone-control adjustment.

This invention is a broad continuation of the disclosure made in Serial Number 473, 316 of May 28, 1921.

The structure shown in the accompanying 45 figures in its accessory relation is largely suggestive, as it is immaterial in what specific kind of a cabinet the invention is installed. As instanced, 1 represents the horn, which in my inventions I have found de-

50 sirable to construct the same of an inert self-setting, non-absorptive and non-resonant composition, so that the sound waves emanating from the usual record will be delivered from the horn without the imposi-

tion thereon of the natural periodicity of 55 the horn itself. Even when the horn is made very heavy, the impact of sound waves at the point 3 of the neck 2 will set up modifying vibrations.

To overcome such stray vibrations, I place 60 a support 7 beneath the neck. It may be made of laminations as shown in Fig. 1 or adjustable as shown in Figs. 3 and 4. The horn is secured to the back 4 of the cabinet by means of a suitable bracket 9 and screws 65 or bolts which pass through side ears 10. The tone arm, record, etc., are shown above the motor board 5. These parts may be of any desired type, but I find superior results when they are coordinated with my 70 present invention and other copending applications, though I do not herein limit myself to any specific form of tone arm, sound box, etc.

In addition I do not limit myself to any 75 particular sources of sound vibrations as the phrase "In a talking machine" used in the claims basically includes either a mechanical acoustical or electrical source of vibration, because the invention is equally 80 adapted to these and any other available sources.

The horn compartment may be between the horizontal partition 6 and the motor board 5. The tone modifying support 7 85 has side ears 8 by means of which it is secured to the partition 6, as exemplified in Figs. 1 and 2; or is suspended from the motor board 5 as shown in Figs. 3 and 4 by means of long bolts 14. In this latter 90 form the support 11 is also curved to the cross section of the horn neck similar to the support or under-saddle 7. This part 11 has slots 12, in side extensions, through which the rods 14 pass loosely as they continue downward through holes in the cross member 13. These bolts are held by nuts 15, either above the motor board 5 or below the cross member 13 as may be desired.

In order that the under-saddle can be adjusted, two adjusting screws 16 are provided. These have a plain stem 17 and a threaded stem 18. The latter enters a threaded hole 19 in the cross member 13 and the ends 17 seat in holes formed on the underside of the "saddle" 11. In this way the upward pressure of the support can be varied, at will, against the horn as it is

supported on the bracket 9 thus overcom-
ing any tendency to "originate" spurious
vibrations in the horn itself.

What I claim is:

- 5 1. In a talking machine, a case, a horn
secured to the rear wall of the case, a motor
board above the horn and a support adapt-
ed to engage the underside of the horn at
the neck said support being suspended from
10 the motor board.
2. In talking machines, a case, a motor

board, an amplifying horn, means for sup-
porting the small end thereof on the case
independently of the motor board, support-
ing means depending from the motor board 15
opposite the curved end of the horn, and
means cooperating with the said support
adapted to subject the neck of the horn to
variable pressure as desired.

In testimony whereof I affix my signa- 20
ture.

BAGSTER ROADS SEABROOK.
